UNITED STATES PATENT OFFICE.

HERBERT S. MILLS, OF CHICAGO, ILLINOIS.

COIN-OPERATED BOX.

No. 918,885.

Specification of Letters Patent.

Patented April 20, 1909.

Application filed October 9, 1908. Serial No. 456,939.

To all whom it may concern:

Be it known that I, HERBERT S. MILLS, a citizen of the United States, residing at Chicago, in the county of Cook and State of Illinois, have invented a new and useful Improvement in Coin-Operated Boxes, of which the following is a specification.

The object of my invention is to provide a construction of box, which I have more particularly devised for affixing it to the back of a theater-seat, to hold a package or packages of candy, chocolates, or the like, contained in the box under confinement releasable by the insertion therein of a coin of proper denomination enabling the box-cover to be unlocked to permit withdrawal of the contents.

In the accompanying drawings, Figure 1 shows my improved box by a view in front elevation in its locked condition with parts of the mechanism inside it represented by dotted lines; Fig. 2 shows the same by a view in end elevation; Fig. 3 is a section on line 3, Fig. 2; Fig. 4 is a view like that presented in Fig. 3, but showing the cover raised to open the box and the mechanism in it brought to the condition it is caused to assume by the unlocking operation, and also showing the coin-releasing key in perspective near the key-way in the box; Fig. 5 is a similar view showing the parts of the mechanism as they appear under the section of the key inserted for releasing the coin, and Figs. 6, 7, 8 and 9 are sections taken, respectively, on lines 6, 7, 8 and 9 Fig. 5.

The box 10 shown, which is preferably formed of metal, is of proper size and shape to hold an ordinary box of candy, chocolates or bonbons, indicated at 11 (Figs. 2 and 3) and seating against a raising-spring 12 on the bottom inside the box, on the back of which is fastened a wooden block 13 having a concave face to conform to and fit against the upper part of the rear surface of the back of a theater-seat (not shown) to which the box is thus adapted to be secured to render it convenient of access to a person in a seat-behind it for the insertion of a coin to permit it to be opened for removing the package 11. On the upper edge of the back of the box is a ledge 14 projecting over the top of the block 13 and having ears depending at its ends to form bearings for a hinge-pin 16 carrying the flanged box-lid or cover 17 at end-ears 18 on its rear corners. A spiral spring 19 connects the cover from near its rear edge with the block 13 in a recess 20 formed thereon, as

most clearly represented in Figs. 1 and 5, this spring operating to raise the cover when the hook-shaped tongue 21 depending from near its free edge is released from the coin-operated locking mechanism hereinafter described.

The front wall of the box is formed of an outer plate 22 and an inner plate 23 spaced apart to provide between them a space 24 for the operating mechanism to work in. The plates contain two openings 26 and 27 (Fig. 1) in vertical alinement with each other midway between the ends of the box, through which to manipulate screws, indicated at 28, passed through the box-back into the block 13 to fasten the box thereon. Between these two plates is formed a coin-chute 29 leading from a coin-insertion opening 30 in the plate 22 near its upper edge to a recess or opening 31 extending into it from its lower edge. The outer plate also contains, for the purpose hereinafter described, a longitudinal slot 32 near its lower right-hand corner; and near the opposite end of the box a hole 33 is formed through both plates, to receive a stud 34. This is a circumferentially grooved stud on the back of a shield-plate 35 provided with a base-flange 36 to project underneath the bottom of the box and having formed on its inner face a boss 37 conforming to and fitting in the recess 31 and of the same thickness as the outer plate 22 to extend flush with its inner surface.

A spring-pressed catch-lever 38 is fulcrumed between its ends on the plate 22 to work in a recess 39 in its back surface and extend with its lower end into coincidence with the recess 31 and with its upper recessed end adjacent to an opening 40 formed between the upper edges of the two plates 22 and 23 to receive the tongue 21 for its releasable engagement with the catch 38 for locking the cover in its box-closing position. A pair of spring-pressed tumblers 41 and 42 are also pivoted to the plate 22 to work within its recess 39 and extend their free ends opposingly adjacent to the stud-receiving hole 33, so that they normally occupy the relative positions represented in Figs. 3 and 4 where-in they project within the groove of the stud 34 to retain it against withdrawal from said hole and thus lock the shield-plate against removal. Each tumbler contains in its free end an arc-shaped recess 43 of a size to correspond with the diameter of the stud 34 when the tumblers are turned to the relative

positions represented in Fig. 5, wherein the recesses in the ends embrace the stud in a manner to permit its free withdrawal through the hole 33. The recesses 43 in the free ends 5 of the tumblers are so arranged as to be, in the normal relative positions of the latter, out of registration with each other, thereby to adapt them to be turned to the unlocking position of Fig. 5 through the medium of a 10 particular key 44 insertible into a key-way 45 formed in the plate 22 and leading to the recess 39 to engage its offset end 46 successively with the upper and lower tumbler near their free ends in the key-path.

15 A spring-retracted plunger 47 works in the space between the plates 22, 23 with relation to the base of the coin-chute 29 and is normally held by its controlling spring 48 in the position represented in Fig. 3 wherein its 20 inner end registers with the adjacent side of the chute. It is movable by a knob 49 on a stem 50 connecting it through the slot 32 with the plunger, which is provided in its upper edge with a ratchet 51 between 25 notches 52, engaged by a spring-pressed pawl 53 pivotally supported in a recess 54 formed in the inner face of the plate 22.

The arrangement of the pawl and ratchet is such as to lock the plunger in any position 30 in its movements, against retraction by the spring 48 until a notch 52 registers with the pawl to free it, thereby necessitating a complete stroke of the plunger for opening the box by the following-described operation: 35 The parts of the mechanism, with the box 10 closed and containing a box 11 of candy, or the like, normally occupy the relative positions represented in Figs. 1 and 3, wherein the hook 21 is engaged by the catch 38 to 40 lock the cover 17 and confine the package 11 under compression against the spring 12. To open the box 10 a coin 55 is inserted into the opening 30 to roll through the chute 29 (which is a recess in the inner face of the 45 plate 22) and lodge in the position represented in Fig. 3 between the lower end or tail of the catch-lever 38 and the plunger 47. By then moving inwardly the plunger, at the knob 49, it encounters the coin in its path, 50 and moves it into registration with the closed recess 31 against the catch-lever, thereby turning the latter to disengage it from the tongue 21 and release the cover 17 to permit the spring 19, supplemented by the spring 12, 55 to raise it. The spring 12 protrudes out of the box 10 the top-portion of the candy-box to render it conveniently accessible for withdrawal. This operation brings the parts to the relative positions in which Fig. 4 represents them, wherein the plunger has made 60 only a part of its inward stroke, being obstructed against further movement in that direction by the head-portion of the catch 38 encountering the wall of the recess 39; and 65 the parts are retained in that condition, by

the engagement between the pawl and ratchet, until the coin is removed. To remove the coin, the person authorized to use the key 44 inserts it against the tumblers to turn them from the position represented in Fig. 4, 70 wherein their inner ends extend into the groove in the stud 34 to obstruct its withdrawal, to that represented in Fig. 5, wherein the tumblers are disengaged from the stud to permit, by its withdrawal through the hole 75 33, removal of the shield-plate 35 to expose and permit access to the coin for taking it out. With the coin taken out the operator 80 may complete the inward movement of the plunger, at the end of which the pawl enters the outermost notch 52 and frees the plunger to permit retraction thereof by the spring 48, in which movement of the plunger the ratchet rides past the pawl. The box is 85 then in condition, after again filling it, to be locked by closing the cover to engage its tongue 21 with the catch 38, then restored by its controlling spring to the normal position. What I claim as new and desire to secure 90 by Letters Patent is—

1. The combination of a box, for the purpose set forth, provided with a cover carrying a locking-tongue, a spring-pressed catch in the box for engaging said tongue, a plunger movable in the box and provided with means for locking it between the ends of its movement, a coin-chute leading from a coin-insertion opening in the box to a point of lodgment therein for the coin between the adjacent ends of the catch and plunger, an opening in the box at said point, a shield-plate covering said opening and provided with an inwardly projecting locking-stud, and spring-pressed pivotal tumblers normally engaging said stud at their free ends to obstruct withdrawal of the shield-plate, and a key-insertion opening in the box with which said free ends register. 100

2. The combination of a box, for the purpose set forth, provided with a cover carrying a locking-tongue and having an inner and an outer plate forming its front wall and a space between them for coin-operated mechanism, a spring-pressed catch for engaging said tongue, a plunger provided with means for locking it between the ends of its movement, a coin-insertion opening and a recess in the outer plate with a coin-chute between them, a stud-opening extending through both plates, a shield-plate fitting in and removably covering said recess and provided on its inner face with a stud to project through said opening therefor into said space, and key-operated tumblers in said space normally engaging said stud. 115

3. The combination of a box, for the purpose set forth, provided with a spring-raised cover carrying a locking-tongue and having an inner and an outer plate forming its front wall and a space between them for coin-op- 120 125 130

erated mechanism, a spring in the bottom of the box, a spring-pressed catch for engaging said tongue, a spring-retracted plunger provided with pawl-and-ratchet locking means, a coin-insertion slot and an opening in the outer plate with a coin-chute leading between them through said space, a stud-opening extending through both plates, a shield-plate removably covering and fitting in said recess and 5 provided on its inner face with a stud to project through said opening therefor into said space, and key-operated tumblers in said space normally engaging said stud.

4. The combination of a box, for the purpose set forth, provided with a spring-raised hinged cover carrying a locking-tongue and having an inner plate and an outer plate recessed on its inner face, said plates forming the front wall of the box with a space between 10 them for coin-operated mechanism, a spring in the bottom of the box, a spring-pressed

catch for engaging said tongue, a spring-retracted plunger provided with pawl-and-ratchet locking means, a coin-insertion slot and an opening in the outer plate with a coin-chute leading between them through said space, a stud-opening extending through both plates, a shield-plate removably covering and fitting in said opening in the outer plate and provided on its inner face with a circumferentially grooved stud to project through said opening therefor into said space, tumblers having recesses in their free ends and pivotally supported in said space to extend said ends adjacent to the stud-opening for locking the stud, and a way in the box leading to said space for a key to disengage the plunger from the stud.
